LOCKER FOR CLOTHES AND THE LIKE

Leonard Schade Van Westrum, Jr., The Hague,
NetherlandsApplication April 15, 1933, Serial No. 666,341
In Germany November 15, 1932

8 Claims. (Cl. 211—8)

This invention relates to an automatic self-cashing burglarproof checking apparatus for clothes and the like, more particularly to such an apparatus consisting of several locking members 5 for the articles to be checked, such as coat, hat, shoes, stick or umbrella, etc., whereby all members are operated from one single shaft.

An object of this invention resides in the provision of an apparatus for checking and locking clothes and the like which is absolutely burglarproof and from which the checked object can not be pulled out.

An object of this invention resides in the provision of an apparatus for checking and locking clothes and the like where the clothes are not hung on their hangers, which may easily be cut, but are held between paws from which they can only be withdrawn by cutting and ruining the clothes.

An object of my invention resides in the provision of a new locker for clothes and the like, the lock of which is always easily accessible and can not be covered by the clothes.

An object of my invention resides in the provision of a self-cashing locker for clothes and the like being of such design as to require very little space and to permit the installation of a plurality of independent lockers extremely close to one another.

A further object of this invention resides in the provision of an open locker for checking clothes and the like having only one common member to be manipulated for locking all objects checked by the same locker.

Further and other objects of the present invention will be hereinafter set forth in the accompanying specification and claims and shown in the drawing which, by way of illustration, shows what I now consider to be a preferred embodiment of the invention.

In the drawing:

Fig. 1 is a front view of a preferred embodiment of my invention.

Fig. 2 is a side view of an apparatus according to my invention in open position.

Fig. 3 is a side view of an apparatus according to my invention in closed position and with a closable box attached which is not shown in Figs. 1 and 2.

Fig. 4 is a side view of a modification of an apparatus according to my invention.

Figs. 5, 6 and 7 show several modifications of a detail of my invention.

Fig. 8 shows other details of my invention.

In the embodiment of my invention according to Figs. 1 to 3, a base plate *a* or the like may be hung on the wall or other support; this plate carries on top the box *b* which contains the automatic cashier with coin examiner—not shown—the lock *c* for the door and the locker lock *d* and also the main operating shaft *e*. The box *f* for the coins is disposed underneath the operating box *b* which need not be opened when taking out the received money. The operating shaft *e* is manipulated by means of a lever *g* which is pivoted to and on the lower side of the box *b* and which is operatively connected to the shaft *e* by means of the links *h* and *i*. The handle of the operating lever *g* points outwards to prevent contact with the hat checked underneath the members *t* and *r*.

By link *k* and lever 20 the main shaft *e* is connected to the straight rail *l* which extends beyond and below the box *b*. The rail *l* operates 20 all moving parts of the checking and locking apparatus. These details are shown on Fig. 8. To the main operating shaft an arm *m* is rigidly connected. In its course a spring *n* is provided which is mounted to the base plate *a*. This 25 spring is operatively in contact with a double lever *o*—*p*. In relieved position the spring *n* prevents the lever arm *p* from swinging downward. When the spring *n* is compressed by the arm *m*, the lever *o*—*p* which is normally held in 30 position as shown by a member not shown is turned in clockwise direction by this member which is operated through the locker lock *d*. The arm *o* lays itself against the catch 23 of arm *m*, thereby keeping this arm in position and locking the operating lever *g* and with it the operating rail *l*. A self-cashing mechanism may be interposed between the locker lock *d* and the member not shown, this self-cashing mechanism preventing operation of lock *d* unless a coin is 35 inserted. By manipulating the lock *d* again, the lever *p* is turned upward assisted by the tension of spring 22, the arm *m* is free and can be turned upward by operating the handle *g* in a counter-clockwise direction. The spring *n* lays itself again against the lever *o*, thereby locking the apparatus in open position, i. e., in a position where the clothes can be removed or inserted. At the same time the mechanism not shown but connected to double-lever *o*—*p* takes care that 40 the key for operating the locker lock *d* cannot be withdrawn from this lock until the lever *g* is pulled down again and another coin is inserted.

The self-cashing mechanism which is not shown thus prevents locking the apparatus and 55

taking out the key unless the correct coin is inserted.

Below the coin box *f*, the locking members for hat, coat stick or umbrella, and containers for 5 shoes etc. are provided. The locking device for the hat consists of three parts: the arm *r* which is rigidly connected to the main rail *l* and the im- 10 moveable arm *s* mounted to the base plate *a*. The arm *s* may be provided with an eye 21 through 15 which the main rail *l* can move up and down. In between the arms *r* and *s* a swinging arm *t* is pivoted to the rail *l*, which arm serves as a rest 20 for the brim of the hat. The arms *r*, *s* and/or *t* are provided with felt, plush, bristles, rubber pads 25 or the like where they come into contact with parts of the hat to prevent spoiling of the hat material and to increase the friction between the arms and the hat and to prevent pulling out of 30 the hat or object held between the arms.

The locker for the coat consists of two parts: the arm *u* is rigidly connected to the rail *l* and carries the paws *v* at its end. The inside of the 25 paws *v* is covered with felt or the like and is provided with a rubber roll *w*. The stationary part 30 of the coat locker is positioned below the paw *v*. It is mounted to an angle-support *x*, through which the rail *l* slides, and consists of a counter-paw *y* which rests on a bent plate spring *z*, (Fig. 2). Paw *y* is rigidly connected to the spring *z*, the latter being mounted to the support *x*.

Close to the lever end of the rail *l*, a spring clamp 2 is provided for the stick or umbrella; below the clamp 2 are two halfmoon like brackets 35 3 which are part of double levers 4-5 and pivoted to the baseplate *a*. The lower arms 5 of the double levers 4-5 are operated by the lower end of 40 the rail *l*.

In the embodiment of my invention according 45 to Fig. 3, a container 6 is provided which may rest on the ground and has a lid 7. This container can be used for checking shoes etc. The container 6 is also closed and locked by the rail *l*.

Figs. 1 and 2 show the apparatus in rest position. Operating lever *g* is moved upward and the 45 bracket or clamp for the coat, hat and stick are open; the key for locking the lock *d* and the checking apparatus can not be pulled out. First, the stick or umbrella is inserted into clamps 2, then 50 the coat is hung over the paw *y* by its collar, last the hat is put on the swinging arm *t*. Then the operating lever is pulled downward as shown on Fig. 3. The rail *l* which is pushed down when lever *g* is pulled closes all clamps, whereby hat, 55 coat, stick and container are all locked up. The swinging arm *t* of the hat clamp abuts against the rest arm *s* and is fixed by the further movement of the arm *r* which is pressed against the swinging arm *t*. By this operation, the hat brim 60 is clamped so fast that the hat can not be withdrawn. Due to the resiliency of the support *y*, even thin coats, such as silk raincoats, cannot possibly be withdrawn from the closed locker. 65 If one pulls on the coat on the bracket, the support cushion *y* swings in the direction of the pull— as indicated by the dotted line on Fig. 5—and the coat is only clamped more tightly. The rubber roll *w* in the paw *v* prevents excessive pressing 70 of the clamped coat.

In container 6, shoes and other articles may be checked. The rail *l* places cover 7 onto container 6, thereby locking the container.

After insertion of the coin, the apparatus is 75 locked by locking the lock *d*, and the key can be

withdrawn. The articles are then checked in a burglarproof manner.

In the embodiment of my invention according to Fig. 5, the ends 8 of the paw *y* are loosely pushed into the casing 9 but can not be withdrawn from the latter.

In the embodiment of my invention according to Fig. 6, the part *y* is replaced by two swinging members 11 which revolve around the bolts 10. Their extreme ends are rounded and match the 10 hollow shell like parts of the paw *v*.

The embodiment according to Fig. 7 shows how the coat support *y* may be resiliently mounted on springs 12 which, in turn, are mounted to the stationary support *x*.

The embodiment of my invention according to Fig. 4 differs from that according to Figs. 1 to 3 in that the bracket arrangement for holding the hat only consists of two parts, whereas in the design as per Figs. 1 to 3 it consists of three parts. The swinging arm *t* is omitted, and arm *s* serves as support for the hat. The support 13 for the upper coat clamping paw *v* is rigidly connected to the arm *r* for the hat. The movable parts of the hat and coat locker are combined in one common member. Instead of the operating lever at the side of the box *b* as per Figs. 1 to 3, a U-shaped member is provided on top of the box *b*. This has the advantage that the sides of the apparatus are free and it can be placed very close to the next locker.

The box 6-7 may also be placed above the brackets for stick or umbrella; it may contain another small container for pocketbooks, jewelry and other valuables and may be arranged to 35 be individually locked.

While I believe the above described embodiments of my invention are preferred embodiments, I wish it to be understood that I do not desire to be limited to the exact details of process, design and construction shown and described, for obvious modifications will occur to a person skilled in the art.

What I claim is:

1. A selflocking burglarproof apparatus for 45 checking clothes consisting of a plurality of movable members for holding the individual clothes; a box containing a selflocking mechanism, an operating shaft within said box, a rail extending downwards from said box, said rail being operatively connected to all of said movable members and also to said operating shaft, an arm rigidly connected to said operating shaft, a compressible 50 spring member and a locking lever within said box, said spring member, when in a non-compressed state, operatively engaging said locking lever and holding it in position, said arm engaging and compressing said spring member upon operation of said operating shaft and thereby liberating said locking lever.

2. A selflocking burglarproof apparatus for 55 checking hats and clothes consisting of a locking mechanism, an operating rail extending downwards from said locking mechanism, a base, and a member rigidly connected to said operating rail, a member pivoted to said operating rail; and a rest arm connected to said base and serving as a rest for said pivotally connected member, said rigidly connected member and said pivotally connected member in cooperation adapted to hold 60 and lock a hat in between said members.

3. A selflocking burglarproof apparatus for 65 checking hats and clothes consisting of a locking mechanism, an operating rail extending downwards from said locking mechanism, a base, and 70

a member rigidly connected to said operating rail and having a shell shaped part internally provided with cushioning material, and a support member rigidly mounted to said base, both members adapted to hold a coat collar in between said members, said support member having yielding resilient provisions for resiliently and yieldingly pressing the coat collar against said member connected to said operating rail, said yielding resilient provisions allowing a sideward movement.

10 4. A selflocking burglarproof apparatus for checking hats and clothes consisting of a locking mechanism, an operating rail extending downwards from said locking mechanism, a base, and a member rigidly connected to said operating rail, and having a shell shaped paw internally provided with cushioning provisions, and a support member rigidly mounted to said base, both members adapted to hold a coat collar in between them, said support member having movable provisions exerting a key action upon said coat collar and said shell shaped paw when said coat is pulled on.

15 5. A selflocking burglarproof apparatus for checking hats and clothes consisting of a locking mechanism, an operating rail extending downwards from said locking mechanism, a base, and a member rigidly connected to said operating rail and having a shell shaped paw internally provided with cushioning material, and a resilient buffer, and a support member rigidly mounted to said base, both members adapted to hold a coat collar in between said members, said support member having spring provisions for yieldingly and resiliently pressing the coat collar against said member connected to said operating rail, said spring provisions allowing a sideward movement.

20 6. A selflocking burglarproof apparatus for checking hats, coats and umbrellas consisting of

a locking mechanism, an operating rail extending downwards from said locking mechanism, a base, and a member rigidly connected to said operating rail, and a rest arm connected to said base, said arm adapted to hold the hat and said member adapted to press the hat against said rest arm, and an extension on said member, and a support for a coat, said support being rigidly mounted on said base, said extension cooperating with said support upon operation of said operating rail and locking the coat between said extension and said support.

25 7. A self-locking burglar-proof apparatus for checking clothes and other objects consisting of an operating and a locking mechanism, an operating rail extending from said operating mechanism, stationary and movable individual members for holding the individual clothes and other objects, said rail being operatively connected to all of said movable members, said operating and locking mechanism being freely accessible at all operating conditions and located above all of said individual members and an entirely selfcontained casing independent from all of said members and entirely enclosing said operating and locking mechanism.

30 8. A self-locking burglar-proof apparatus for checking clothes consisting of a locking mechanism, an operating rail extending downwards from said locking mechanism, stationary and movable individual members for individually holding a hat, a coat, a stick or umbrella, and a base plate, said stationary members being mounted on said base plate and including a container for shoes and the like, and said movable members being mounted on said operating rail and including a cover for said container.
